UNITED STATES PATENT OFFICE.

WILLIAM HENRY DAVID AND DEE TILDEN GRIFFIN, OF ATLANTA, GEORGIA.

LAUNDRY-TABLE.

1,279,665.

Specification of Letters Patent. Patented Sept. 24, 1918.

Application filed May 15, 1917. Serial No. 168,749.

To all whom it may concern:

Be it known that we, WILLIAM H. DAVID and DEE T. GRIFFIN, citizens of the United States, residing at Atlanta, in the county of 5 Fulton and State of Georgia, have invented a new and useful Laundry-Table, of which the following is a specification.

This invention has reference to laundry tables and is designed to provide a table in 10 which rough dried laundry may be stored, on which the laundry may be ironed, and which is arranged for holding the ironed laundry, with the structure so arranged that when not in use as a laundry table it may 15 be employed as a kitchen or dining room table.

The invention comprises a table structure with a body portion constituting a receptacle and a divided top having one part fast 20 to the body portion and the other part hinged to the first part, so as to expose the interior of the body portion to access. The table is provided with a normally hidden ironing board exposed when the hinged sec- 25 tion of the top is turned back, and the hinged portion of the top carries posts hinged thereto and arranged for the reception of rods holding the posts in upright position and constituting supports for 30 ironed clothes.

The invention will be best understood from a consideration of the following detailed description, taken in connection with the accompanying drawings forming part 35 of this specification, with the further understanding that while the drawings show a practical form of the invention, the latter is not confined to any strict conformity with the showing of the drawings, but may be 40 changed and modified so long as such changes and modifications come within the scope of the appended claims.

In the drawings:—

Figure 1 is a perspective view of the table 45 in position for ironing.

Fig. 2 is a longitudinal section of the table through the hinged portion of the cover, showing the posts and connecting rods housed in the table.

Fig. 3 is a cross-section of the table near one end.

Fig. 4 is an elevation of the table open as in Fig. 1, but viewed from the side of the table remote from that seen in Fig. 1.

Referring to the drawings there is shown 55 a table 1, comprising a body portion 2 sup-

ported upon legs 3, the body portion having a bottom 4 and one long side 4^a inset for a distance from the corresponding side of the table. The body portion 2 is covered by a 60 top formed of sections 5, 6, respectively, connected by hinges 7, so that the section 6 may be turned back upon the section 5, thus exposing a part of the body portion forming a receptacle 8 which, when the table is 65 employed as a laundry table, may contain rough dried clothes. The body portion 2 has end pieces 9, 10, of greater length than the width of the receptacle 8, and between the side 4^a of the receptacle 8 and the adjacent legs 3 of the table the ends 9 provide ledges for the support of an ironing board 11, which may be of the usual type and connected at one end, say, the larger end, to the corresponding end piece 10 of the body 70 by hinge connections 12. In this manner the ironing board is conveniently located, is firmly supported without liability of displacement, and the small end may be raised 75 for placing articles of clothing thereon for 80 ironing.

Connected to what normally constitutes the lower face of the table top section 6 by hinges 13, is one end of each of two posts 14 so located that when these posts are 85 folded against the corresponding face of the top section 6 their combined length is less than the available length of the compartment 8, wherefore when the table top section 6 is folded down level with the section 5, the posts 14 folded adjacent to the table top section 6 may be lodged within 90 the compartment 8.

The posts 14 have eyes 15 or other holding devices on what constitutes their upper ends, 95 that is, the ends remote from the hinges 13, and along one side of each post are other eyes 16, the eyes 16 of one post matching those of the other. There are also provided rods 17, 18, respectively. The rod 17, of 100 which there may be but one, without, however, limitation to such number, has terminal pins 19 projecting therefrom. The rods 18, shown as two in number in the drawings without limitation to such number, have terminal hooks 20. These rods 17 and 18 with their pins and hooks are of such length as to be storable within the compartment 8, when not in use, in addition to the posts 14.

When the table is employed for ironing 110 purposes the cover member 6 is moved to the open position and folded down upon the

cover member 5, the posts 14 are erected and the rods 17 and 18 are connected to the eyes 15 and 16, respectively, by the pins 19 and hooks 20, thus forming a rack upon which 5 ironed clothes may be hung.

When the ironing is finished and the ironed pieces are removed from the rack, the bars or rods 17 and 18 are removed from the posts 14 and the latter are folded down 10 against the table top section 6. Then the section 6 is turned on the hinges 7 away from the section 5 until on a level therewith, in which position the posts 14 are contained within the compartment or receptacle 8, into 15 which latter the bars or rods 17 and 18 have been previously placed. The table top section 6 is wide enough to not only close the compartment 8 but to cover and hide the ironing board 11, wherefore the table when 20 in the closed position may be utilized as a kitchen table, or even as a dining room table.

What is claimed is:—

1. A table provided with a divided top having one section hinged to and foldable 25 onto the other, posts hinged to the under-face of the foldable section of the table top and also foldable thereagainst, and bars applicable to the posts to hold the latter in erected position and together with the posts 30 constituting a clothes supporting rack on the table.

2. A table provided with a compartment, a divided top forming a cover for the compartment and having one section hinged to 35 and foldable from a level with the other section onto said section in overlying relation thereto, posts hinged to the under face of the foldable section of the table top close to the hinged edge thereof, and bars applicable to the posts to hold the latter in erected 40 position and together with the posts constituting a clothes supporting rack on the

table, the clothes rack being related to the compartment in the table to house therein when in the folded condition and with the 45 foldable member of the cover closed.

3. A table comprising a body portion having extended end pieces, one side inset, and a bottom, the extended end pieces providing supports for an ironing board beyond the inset side, a divided cover having one part fast to the body portion to form a partial closure therefor, and the other section of the cover being hinged to the first section to be folded thereonto and of a width 55 to complete the closure for the body portion and to overlie the extended end pieces, posts hinged to the foldable section of the cover on the under face thereof adjacent to its hinged edge and movable about its hinges 60 to an upright position when the foldable section is moved onto the fixed section, and bars of a length to extend between the posts and together with the posts having coacting means for connecting the bars to the posts to thereby constitute a rack.

4. A table provided with a divided top having one section hinged to and foldable onto the other section, and a clothes supporting rack on the under face of the hinged section and extending lengthwise thereof, said rack comprising end posts and removable rack bars, with the end posts hinged to the top section carrying them and foldable thereagainst toward each other.

In testimony that we claim the foregoing as our own, we have hereto affixed our signatures in the presence of two witnesses.

WILLIAM HENRY DAVID.
DEE TILDEN GRIFFIN.
